To all whom it may concern:

Be it known that I, CHARLES A. 10 Figure 1 is a side view of the kettle. Fig. 2 is a front elevation of the same. Fig. 3 is a rear elevation, and Fig. 4 is a top plan view.

This invention has relation to a certain new and original design for tea-kettles; and it consists in the novel configuration of parts, as 15 hereinafter described, and illustrated in the accompanying drawings.

Referring to the drawings, the body A of the kettle is ornamented with a narrow cen-

Around the upper part of the kettle-body extends an ornamental flower-and-vine 25 figure *a*². The top or cover B of the kettle is ornamented with a circular flower or fluted figure b, as shown in Fig. 4.

The spout of the kettle is ornamented with the series of longitudinal grooves or lines c. 30
